(57) **CLAIM**

The ornamental design for a self-checkout station, as shown and described.

DESCRIPTION

FIG. 1 is a perspective view of a self-checkout station showing our new design.

FIG. 2 is a left side view thereof.

FIG. 3 is a front side view thereof.

FIG. 4 is a right side view thereof.

FIG. 5 is a rear side view thereof.

FIG. 6 is a top view thereof; and,

FIG. 7 is a bottom view thereof.

The broken lines in the drawings illustrate portions of the self-checkout station that form no part of the claimed ornamental design. The shading is used to represent surfaces of the self-checkout station.

1 Claim, 7 Drawing Sheets
